UNITED STATES PATENT OFFICE

FRANCIS J. McMURDIE, OF KALAMAZOO, MICHIGAN, ASSIGNOR TO CLARAGE FAN COMPANY, OF KALAMAZOO, MICHIGAN

FAN WHEEL

Application filed August 19, 1927. Serial No. 214,079.

The objects of the invention are:

First, to provide such a structure which is simple and in which the blades are strongly supported at frequent intervals.

Second, to provide such a structure in which the number and position of blades can be varied without multiplicity of patterns.

Objects relating to details of construction and operation will appear from the detailed description to follow. The invention is defined in the claim.

A structure showing a preferred embodiment of my invention is illustrated in the accompanying drawing, in which:

Fig. 1 is a central sectional elevation of a fan embodying the features of my invention, taken on irregular line 1—1 of Fig. 2.

Fig. 2 is an end elevation view from the intake side of the fan, a portion being in section on the irregular section line 2—2 of Fig. 1, the position and relation of the blades being indicated by dotted lines on the cut-away portion.

Fig. 3 is a detail view of one of the developed blades, showing its slitting at the mid portion and projecting tenons at the ends.

Fig. 4 is an enlarged detail partial sectional view showing the welding at the end of one of the blades, taken on line 4—4 of Fig. 2.

Fig. 5 is a detail view showing the welding of one of the blades to the intermediate rings.

The parts are identified by numerals of reference which are the same in all views.

1 is the cast hub of conical form. 2 is the back plate of the fan wheel suitably flanged at 21. 3 is the front ring forming the intake aperture by the flange 4. 5 are the peripherally disposed fan blades in volute arrangement. 6 and 7 are the intermediate supporting rings, each ring being a cone section. The fan blades 5 are provided with tenons 53, 53 for securing them to the fan back plate 2 and with tenons 54 for securing them to the front ring 3, and are slotted at 51 at their outside margins and at 52 at their inside margins, as seen in Fig. 3. The intermediate outer ring 6 is disposed in the outer slot 51 and the ring 7 is disposed in the inner slot 52, the rings 6 and 7 being sections of the same cone. 50 They are welded by electric or acetylene

welds to the sides of the slots of the blade, thereby making very strong support. The blades can of course be very readily adjusted to these rings, and as they are secured by welding it is possible to insert a great variety 55 of blades at various angles depending on the service required of the fan. Also, the rings 6 and 7 are very readily applied at any point intermediate the length of the fan blades, thus enabling long blades to be readily installed and also making possible the use of 60 light weight material in the blades. These intermediate rings act very much like tires to hold the blades in position. I am aware that flat rings have been inserted and secured by 65 rivets. In such the rivets are expensive and result in numerous perforations and weakening and also present imperfect surfaces, causing undue friction.

The outer ring 3 of the fan is connected by 70 diagonally-disposed radial brace bolts 8 to the hub, three or more in number, six being here shown, the same being adjustable by the lock nut 9 at the inner end and by the adjusting lock nuts 10 and 11 at the outer end. The fan 75 wheel of course is capable of being used in various relations.

Having thus described my invention, what I claim as new and desire to secure by Letters Patent is:

A fan wheel comprising a suitable hub, a circular back plate secured thereto, a front fan ring open to form an intake at the center, peripherally-disposed volute fan blades slotted at their mid portions on their outside 85 margins and on their inside margins, and tenoned into said back plate and front ring and welded at the tenons, and intermediate rings of conical sections disposed in said slots in each of said blades outside and inside, and 90 welded at the meeting points of the slots in the blades to the rings whereby the full tensile strength of the rings is preserved with minimum obstruction to air flow, as specified.

In witness whereof I have hereunto set 95 my hand.

FRANCIS J. McMURDIE.
